AIR STERILIZER

Frank H. Haines, Baltimore, Md., assignor to
Standard Engineering Company of Washington,
D. C., Inc., a corporation of Delaware

Application December 14, 1948, Serial No. 65,229

10 Claims. (Cl. 219—39)

1

The present invention relates to improvements in air sterilizers and has for an object the provision of such a device for the killing of any disease carrying germs which are present in the air in hospitals, assembly halls and the like.

Another object of the present invention is to provide an improved structure of this character in which disease carrying germs are destroyed before the air is exhausted into the open atmosphere or recirculated into a building or the fresh air supply into a building.

A further object of the present invention is to provide an improved air sterilizer in which an air diverter is positioned adjacent the inlet of the heating chamber so that the incoming vitiated air is caused to flow into direct contact with the heating units. This is the most restricted portion of the air conduit and imparts to the device the advantage that the heating elements in this area have considerably less space and volume of incoming air to heat so that the temperature of this relatively cool air can be initially raised a relatively large amount. From this restricted area the air conduit gradually increases in size towards the outlet of the sterilizer in order to permit the expansion of the air as it progressively increases in temperature in its passage through the heating chamber.

A still further object of the present invention is to provide an improved device of this character in which the temperature of the germ laden air is raised to the desired degree by two methods of heating which are carried on simultaneously, namely, conduction and convection.

The present invention aims to provide an improved structure which is automatic in operation and has relative few moving parts to wear out and be replaced.

The present invention contemplates in one of its broadest aspects the provision of an improved air sterilizer comprising a casing having an air inlet at one end and an air outlet at its opposite end, a series of spaced apart heating elements disposed within the casing between its inlet and outlet and a diverter for directing the incoming air into direct contact with said heating elements.

It is another aim of the present invention to mount the heating elements and the diverter upon a base plate which in turn is detachably connected to the casing so that by merely loosening a few bolts the base plate with the heating elements and the diverter mounted thereon can be easily and quickly removed from the casing as a unit for the purpose of making repairs or replacement.

With the foregoing and other objects in view, the invention will be hereinafter more fully described and more particularly pointed out in the appended claims.

2

In the drawings, in which the same parts are denoted by the same reference numerals throughout the several views;

Figure 1 is a front elevational view of the improved air sterilizer constructed in accordance with the present invention;

Figure 2 is a side elevational view of the same;

Figure 3 is a vertical sectional view of the improved device with parts in elevation;

10 Figure 4 is a fragmentary bottom plan view of the base plate;

Figure 5 is a transverse horizontal sectional view on the line 5—5 of Figure 3;

15 Figure 6 is a vertical sectional view through one of the insulators shown in Figure 5; and

Figure 7 is a fragmentary diagrammatic view of the lower end of the improved device showing the base plate, the heating elements and the diverter partially withdrawn from the casing as 20 an integral unit.

25 Referring more particularly to the drawings, 10 indicates the outer wall of a cylindrical metal casing. The casing includes an inner wall 11 which is concentric with and spaced from the outer wall 10. A reinforcing band 12 is secured by welding or the like to the inner face of the outer wall 10 at the lower end portion thereof. A similar reinforcing band 13 is secured by welding or the like to the outer face of the inner wall 11 at the lower end portion thereof. An insulating ring 14 is attached by welding or the like to the lower ends of the walls 10 and 11 and to the bands 12 and 13 for closing the lower end of the casing. Insulating material 15, such as sheet asbestos or the like, is secured to the under face of the ring 14. The space between the inner and outer walls 10 and 11 is filled with insulating material 16, such as glass wool or the like.

30 A base plate 17 is detachably connected to the ring 14 by bolts or the like 18 and is provided with an opening through which extends an annulus 19. The lower end portion of the annulus 19 extends below the base plate 17 and the upper end of the annulus is received by a suitable opening in a circular plate 20.

35 Brackets 21 are attached by welding or the like to the under surface of the plate 20 and to the outer face of the annulus 19. Brackets 22 are secured to the under surface of the plate 20 and to the inner face of an upstanding ring 23. 40 Brackets 24 are secured as by welding or the like to the outer face of the ring 23 and the upper surface of the base plate 17.

45 A top reinforcing band 25 is secured to the inner surface of the upper end portion of the wall 10 and together with the upper end of the wall 10 supports a top plate 26, having a suitable opening for the reception of a ring 27 which extends below and above the top plate 26. An 50 annulus comprising a lower annular flange 28,

an upwardly and inwardly inclined wall 29 and an upper annular flange 30 provides a continuation of the inner wall 11 of the casing. The inner face of the flange 28 is secured by welding or the like to the outer surface of the upper portion of the wall 11 and the outer face of the flange 30 is secured by welding or the like to the inner surface of the ring 27.

Intermediate its upper and lower ends the wall 19 has secured to its inner surface a reinforcing band 31 and to its outer surface mounting brackets 32 having suitable openings adapted to receive threaded supporting rods provided with nuts by which the casing can be suspended from the ceiling of a room. Four vertically extending standards 33 angularly spaced apart about ninety degrees are disposed within the space defined by the wall 11 and are spaced inwardly therefrom. The standards have apertured feet 34 for the reception of bolts 35 which also extend through the bottom plate 17 and the circular plate 20 and receive nuts 36 thereon for mounting the standards on the base plate 17. The bolts 35 are surrounded by spacers 35a.

A set of vertically aligned and spaced apart supporting rings 37 is secured by welding or the like to the inner faces of the standards 33. A second set of similarly arranged supporting rings 38 is secured to the outer faces of the standards 33 in vertically staggered relation to the rings 37. A plurality of porcelain insulators 39 are mounted on the rings 37 and 38. As shown in Figure 6, each insulator 39 is substantially H-shaped and has a rectangularly shaped longitudinal groove 40 in its upper surface and a similarly shaped groove 41 in its lower surface. Each insulator has a square medially disposed longitudinal passageway 42. As shown in the upper righthand portion of Figure 5, the first insulator 39 of each concentric row is secured to its respective ring 37 and 38 by a bolt 43 and a nut 44 and every third insulator in each row is similarly attached by bolts to its ring. A square shaped tie rod 45 extends through the passageway 42 of two adjacent unbolted insulators 39 and has its opposite end portions received by the passageways 42 of the contiguous bolted insulators so that its ends abut the bolts 43 therein to keep the tie rods from longitudinal shifting.

A series of vertically spaced apart electric resistance heating elements 46 are disposed within the heating chamber defined by the wall 11 by having their opposite edge portions received by the grooves 40 and 41 of adjacent insulators which are mounted on the rings 37. A second series of vertically spaced apart electric resistance heating elements 47 are mounted within the heating chamber in vertically staggered and overlapping relation to the series of heating elements 46. The opposite edge portions of each heating element 47 is received by the grooves 40 and 41 of the insulators 39 which are mounted on the rings 38. A diverter 48 has a lower end portion 49 of inverted cone shape and is mounted within the heating chamber by brackets 50 which are secured to the standards 33 by bolts 51 and nuts 52.

The upper portion of the diverter 48 is circular and its outer surface 53 tapers upwardly and inwardly from the base of the inverted cone shaped portion 49 so that the space 54 between the tapered outer surface 53 and the inner surface of the wall 11 progressively increases in cross-sectional area towards the outlet 27. The portion 49 of the diverter 48 is disposed immedi-

ately above the annulus 19 the opening of which constitutes the inlet of the casing.

The electric circuit for the heating elements is of the three phase type and comprises electric conductors 55, 56 and 57 which are connected to terminals 58, 59 and 60, respectively, and to the heating elements. The terminals are mounted in a terminal box 61 and are connected to a suitable source of electric current. The terminal box 61 is mounted on the base plate 17 by screws or the like 62. The conductors are covered by porcelain beads or sleeves 63.

A switch 64 controls the supply of electric current to the heating elements 46 and 47. A pipe 65 has one end connected to the outlet rings 27 and its opposite end is adapted to open to the atmosphere or to recirculate the air into the room in which the device is located. A damper 66 is pivotally mounted within the pipe 65 by a rod 67. One end of the rod 67 projects from the pipe 65 and is secured in a slot 68 of a link 69 by a cotter pin 70. A pin 71 has one end portion riding in the slot 68 and secured therein by a cotter pin 72. The opposite end portion of the pin 71 is connected to the upper end of a lever 73. The lower end of the lever 73 is operatively connected to a thermostat 74, the operation of which is automatically controlled by the temperature of the air within the pipe 65.

In order to operate the thermostat 74 and the damper 66, there is provided a thermocouple disposed within the pipe 65 with wires 75 and 76 extending outwardly therefrom and into a switch box 77, where they are connected electrically in a suitable manner to operate said thermostat. This thermostatic control does not per se constitute a part of the present invention, and it is to be understood that any suitable automatic means may be employed whereby the temperature of the air within the pipe 65 automatically actuates a thermostatic means to thereby operate a damper to open the same dependent upon the temperature of the air within the pipe 65. The thermostatic control is set so that the air within the pipe 65 reaches such a high temperature that all germs are killed before the thermocouple operates to open damper 66 to allow the air to flow through the system and to the open atmosphere or to some suitable recirculation apparatus.

In the operation of the device the sterilizer can be suspended by the brackets 32 from the ceiling of the room in which it is desired to sterilize the air. The vitiated air will normally ascend toward the ceiling and will enter the opening in the annulus 19.

The incoming air will be directed by the inverted cone shape portion 49 of the diverter 48 to the lowermost of the heating elements 46 and 47 immediately upon its entrance into the heating chamber.

The lowermost heating elements 46 and 47 increase the temperature of the incoming air by convection, that is the lowermost portion of the wall 11 is heated by the lowermost heating elements and this heat is imparted to the incoming air. At this entrance zone the column of air is relatively narrow and the heat from the lowermost heating elements reaches the entire column of air. From this point on, due to the upward and inward tapering of the wall 53 of the diverter, the air passage 54 progressively increases in cross-sectional area so as to permit the air to expand as its temperature increases.

As the air flows through the passageway 54, it will be subjected continuously to the heat ema-

nating from the heating elements of the staggered series of elements 46 and 47. As the air progresses upwardly through the passageway 54 in addition to being heated by convection the mass of air adjacent the diverter 48 will be heated by conduction.

The thermostat 74 can be set to become effective for opening the damper 66 at any desired temperature; the preferable range is somewhere between 600 to 700 degrees F. When the air within the heating chamber has reached the proper selected temperature, the thermostat will be operated to pull the lever 73 downwardly so that the link 69 is rocked in a clockwise direction and the damper, through its connection 67 with the link 69, is moved to open position. The air which has then been properly sterilized, due to the destruction of the entrained germs, flows through the pipe 65 and is discharged into the open atmosphere or is recirculated to a fresh air supply of the building. By means of the switch 64, the flow of electric current to the heating elements 46 and 47 can be manually controlled. If desired, a fan can be mounted within the pipe 65 for supplementing the movement of the air from the pipe 65. The device has a capacity of about 75 cubic feet of air per minute.

It will be noted from Figures 3 and 7 that the heating elements 46 and 47, the diverter 48, the inlet 19 and their supporting structure and the terminal box 61 are all carried by the base plate 17 which in turn is detachably mounted on the casing so that by loosening the bolts 18 the base plate with the heating elements, diverter, inlet and terminal box and its connections can be withdrawn from the casing as an integral unit. Repairs can then be made with facility or if the repairs required are too extensive to be made in situ, a new unit can be installed in the casing.

The thermocouple can be adjusted so that the damper will be opened when the temperature in the pipe reaches about 650° F. but the damper will not be closed until the temperature in the pipe 65 falls below 600° F. This will assure that the temperature in the casing will be sufficiently high to kill the germs in the air before releasing the air to the outside atmosphere and also that the egress of the hot air will not be stopped before the air in the casing has cooled sufficiently to prevent burning out of the various parts disposed within the casing.

It is obvious that various changes and modifications may be made in the details of construction and design of the above specifically described embodiment of this invention without departing from the spirit thereof, such changes and modifications being restricted only by the scope of the following claims.

What I claim is:

1. An improved air sterilizer comprising a casing having an inlet opening at one end and an outlet opening at its opposite end, an annular series of vertically spaced apart heating elements mounted within the casing between its open ends, and a second annular series of vertically spaced apart heating elements mounted within the casing in vertically spaced apart and horizontally offset relation to the heating elements of the first series of heating elements.

2. An improved air sterilizer as claimed in claim 1 characterized by the fact that the inner surface of said casing is substantially vertical, that a diverter is mounted within the casing having a leading end of inverted cone shape and that the rear portion of the diverter has an upwardly

and inwardly tapering wall cooperating with the inner vertical surface of said casing so that a passageway of progressively increasing size is provided between the inner surface of the casing and the tapered wall of the diverter.

3. An improved air sterilizer as claimed in claim 2 characterized by the fact that a pipe is connected to the outlet opening of the casing and that a thermostatically controlled damper automatically opens and closes the passageway through the pipe.

4. An improved air sterilizer as claimed in claim 10 characterized by the fact that a series of vertically spaced apart rings are secured to the inner faces of said standards, that a second series of vertically spaced apart rings are secured to the outer faces of said standards and in staggered relation to the first series of rings, that insulators are mounted on each series of rings, that the series of heating elements are mounted on the insulators on the first series of rings, and that a second series of heating elements are mounted on the insulators on the second series of rings.

5. An improved air sterilizer as claimed in claim 4 characterized by the fact that each of said insulators has grooves in its upper and lower surfaces for the reception of the heating elements.

6. An improved air sterilizer as claimed in claim 5 characterized by the fact that the insulators on each ring are disposed in an annular row, that every third insulator has a bolt passing therethrough for securing it to its ring, that each insulator has a square shaped longitudinal passageway therethrough, and that a square shaped tie rod has its opposite end portions received by the square passageways in the bolted insulators, its opposite ends abutting the bolts in the bolted insulators and its intermediate portion extending through the square shaped passageways in the intermediate insulators.

7. An improved air sterilizer comprising a casing having an air inlet and an air outlet, a base plate detachably mounted on said casing and having an opening therethrough, a ring mounted on the base plate, a circular plate mounted on the base plate and having an opening therein, an annulus mounted on the circular plate and communicating with the opening therein and extending through the opening in the base plate, a plurality of standards secured to the circular plate and the base plate, electric heating elements secured to the standards, a diverter mounted on the standards, a terminal box secured to the base plate, terminals mounted in said box, and electric conductors connected to the terminals and the heating elements.

8. An improved air sterilizer comprising a heating chamber having spaced apart walls, heating elements disposed within said chamber, a reinforcing band secured to the inner face of each wall adjacent the lower end thereof, an insulating ring secured to the lower ends of the walls and the reinforcing bands for closing the lower end of the space between the walls, insulating material secured to the under face of said insulating ring, a top plate for closing the upper end of the space between the walls, and insulating material filling the space between said walls.

9. An improved air sterilizer comprising a casing having an air inlet at one end and an air outlet at its opposite end, a series of vertically spaced apart heating elements disposed within the casing between its inlet and its outlet, the

lowermost of said heating elements being disposed inwardly of and closely adjacent to said inlet, and a diverter mounted within the casing and having a leading end of inverted cone shape closely adjacent to said inlet and surrounded by 5 said lowermost heating element, whereby the incoming air is directed by the leading end of said diverter directly against said lowermost heating element.

10. An improved air sterilizer comprising a casing having an air inlet at one end and an air outlet at its opposite end; a base plate detachably mounted on said casing; a series of heating elements supported by said base plate for heating the air as it flows from the inlet to the outlet of 15 said casing, a diverter supported by said base plate for directing the incoming air into direct contact with said heating elements, and a plurality of circumferentially spaced apart standards supported by said base plate and supporting said heating elements.
